UNITED STATES PATENT OFFICE.

CHAUNCEY W. WAGGONER, OF MORGANTOWN, WEST VIRGINIA, ASSIGNOR TO WALTER A. JONES, OF MORGANTOWN, WEST VIRGINIA.

HEADLIGHT-LENS.

1,310,721.

Specification of Letters Patent.

Patented July 22, 1919.

Application filed January 18, 1918. Serial No. 212,482.

To all whom it may concern:

Be it known that I, CHAUNCEY W. WAGGONER, a citizen of the United States, residing at Morgantown, in the county of 5 Monongalia and State of West Virginia, have invented new and useful Improvements in Headlight-Lenses, of which the following is a specification.

This invention is an improved lens of 10 the type employed in connection with headlights, automobile lamps, and the like.

One of the objects of the invention is to provide a lens of the character referred to, having means for preventing objectionable 15 and dangerous glare from high powered lamps, such as are now in common use. A further object is to provide a lens having means for breaking up the parallel rays of light from a parabolic reflector, and to 20 diffuse the light so that the roadside will be sufficiently illuminated to make night driving safe. A further object is to provide a device constructed to keep most of the rays of light issuing from a parabolic reflector, 25 within a distance of forty-two inches from the level roadway in front of the vehicle to which the lamp is attached.

The invention will be hereinafter fully 30 set forth and particularly pointed out in the claims.

In the accompanying drawing:—

Figure 1 is a rear face view of an automobile headlight constructed in accordance with the invention. Fig. 2 is a vertical sectional view on the line 2—2, Fig. 1. Fig. 3 is a transverse sectional view on the line 3—3 Fig. 1. Figs. 4, 5, 6 and 7 are detail views illustrating different types of prisms which may be employed.

Referring to the drawing, the lens 10 consists of a circular body of substantially flat glass, upon one side of which is pressed, or otherwise formed, a series of parallel acute angled prisms 11, extending transversely 45 across the face of the lens. The other face of the lens is a plane surface, suitably polished, as indicated at 12, and the periphery of the lens is provided with an annular flat rim 13, the prismatic inner surface being 50 raised above the plane of said rim. It is desirable, although not necessary, that the series of prisms 11, gradually increase in thickness from the top of the lens to the midale of the upper half of the series and

then gradually decrease in thickness to the 55 middle of the whole series, the arrangement being duplicated in the lower half, as clearly illustrated in Fig. 2, whereby the upper half and the lower half of the lens are each provided with prisms which are thickest at the 60 middles of the respective halves and thinnest at the tops and bottoms thereof.

In practice, the prisms 11 serve to refract the light coming from a parabolic reflector, in such a way as to distribute the light on 65 the road in front of a vehicle carrying the lamp to which the invention is attached. To further diffuse the light rays for the purpose of preventing glare, and also to distribute a part of the light to the sides 70 of the roadway, the lens is provided with a plurality of raised prisms 14, of a length corresponding substantially to the width of the prisms 11. The prisms 14 are arranged in a plurality of series of equally spaced 75 vertical rows, the point or narrowest portion of each prism contacting with the base of the next adjacent prism. As shown in Fig. 1, the prisms 14 are of triangular cross section and of substantially pyramidal form, 80 whereby triangular side and top faces are provided, the point of the pyramid pointing downward. If desired however, the prisms may be of the same shape but inverted, as illustrated in Fig. 4. It will be 85 readily understood that the proportions of the prisms 14 of Fig. 1, or of the prisms 14^a of Fig. 4 may be varied without departing from the spirit of the invention. For instance the pyramids may be made much 90 wider at their bases as indicated at 14^b, Fig. 5. Or if desired the prisms may be of substantial conical shape as indicated at 14^c and 14^d in Figs. 6 and 7 respectively.

The advantages and operation of the 95 headlight lens above described will be at once apparent to those skilled in the art to which it appertains. It will be particularly noted that in no case are the parallel rays from a parabolic reflector permitted to pass 100 through the lens without being refracted either downwardly or laterally, thus producing a diffused light without glare.

Having thus explained the nature of the invention, and described an operative manner of constructing and using the same, although without attempting to set forth all 10 of the forms in which it may be made, or all

of the forms of its use, the following is claimed:—

1. A headlight lens of the character described comprising a transparent body having one surface provided with a plurality of parallel, transversely arranged flat faces inclined with respect to the plane of said surface to form prisms shaped to refract rays of light downwardly, and a plurality of vertically disposed rows of relatively small tapered bodies provided with triangular facets positioned to refract rays of light laterally, each body being superimposed upon and extended across an inclined flat face of the lens and of a length corresponding to the width of the face upon which it is superimposed, the smaller ends of said tapered bodies pointing in the same direction with the ends of the bodies of each row in contact, said rows of tapered bodies being separated by substantial spaces whereby the greater portion of the light rays are permitted to pass through the lens without perceptible diffusion or lateral refraction.
2. A headlight lens of the character described comprising a transparent body having one surface provided with a plurality

of parallel transversely arranged flat faces inclined with respect to the plane of said surface to form prisms shaped to refract rays of light downwardly, and a plurality of vertically disposed rows of relatively small tapered bodies provided with triangular facets positioned to refract rays of light laterally, each body being superimposed upon and extended across an inclined flat face of the lens and of a length corresponding to the width of the face upon which it is superimposed, the smaller ends of said tapered bodies pointing upwardly with the ends of the bodies of each row in contact, said rows being separated by substantial spaces, whereby the greater portion of the light rays are permitted to pass through the lens without perceptible diffusion or lateral refraction.

In testimony whereof I have hereunto set my hand in presence of two subscribing witnesses.

CHAUNCEY W. WAGGONER.
